UNITED STATES PATENT OFFICE.

CHARLEY REUTER AND OSCAR SCHILLING, OF WARSAW, ILLINOIS.

REPRODUCER.

Application filed May 31, 1921. Serial No. 473,594.

To all whom it may concern:

Be it known that we, CHARLEY REUTER and OSCAR SCHILLING, citizens of the United States, residing at Warsaw, in the county of 5 Hancock, State of Illinois, have invented a new and useful Reproducer, of which the following is a specification.

This invention relates to phonograph reproducers, the primary object of the invention 10 being to provide a reproducer which will not be effected by jars or vibrations of the machine to which the reproducer is applied, to the end that the record being played will send off regular and unbroken 15 sound waves.

A further object of the invention is to provide means for insuring the proper tension of the stylus in the sound grooves of the record.

20 A still further object of the invention is to provide means for securing the stylus in a perpendicular position, when irregularities are encountered in the record tablet.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

35 Referring to the drawing:—

Figure 1 is a bottom plan view of a reproducer constructed in accordance with the present invention.

Figure 2 is a vertical sectional view 40 through the reproducer.

Figure 3 is an elevational view of the reproducer, a portion of the upper section being broken away.

45 Referring to the drawing in detail, the reproducer forming the subject matter of this invention comprises an upper section 5 and a lower section 6, the upper section being provided with a depending circumferential flange 7 adapted to embrace packing 8, which contacts with the diaphragm 9 of the reproducer, to support the diaphragm in proper relation with the walls of the sections 5 and 6 to permit the same 50 to vibrate.

55 The sections of the reproducer are secured

together, by means of the bolts 10 which pass through the lateral enlargements 11 disposed in spaced relation on the periphery of the sections, there being provided nuts 12 operating on the bolts 10 for drawing 60 the sections into close engagement with each other. Secured to the lower section 6 is a depending arm 13 which has a right angled extremity 14 lying in spaced relation with the lower section of the section 6, the right 65 angled extremity 14 being provided with a tapered opening to accommodate one end of the pivot pin 15 which has its upper extremity seated in a tapered opening in the section 6, so that the pin may move freely 70 to accomplish the automatic adjustment of the stylus support to be hereinafter more fully described.

Secured to the pivot pin 15 at a point intermediate its ends, is a bearing member 16 75 which has spaced arms 17 through which extend the pivot pin 18 that connects the stylus support 19 to the bearing member 16. Encircling the pivot pin 18 is a coiled spring 20 which has one end contacting with the 80 bearing member 16, the opposite end thereof being passed through a suitable opening in the lug 21, secured to the bearing member 16, the action of the spring 20 being to normally urge the stylus support 19 away 85 from the body portion of the reproducer.

The outer extremity or free end of the stylus support is forked to provide the arms 22 which lie under the angularly disposed arms 23 of the keeper 24, which depends 90 from the lower section 6 of the reproducer, the same being secured to the reproducer at a point directly opposite to the point of connection between the arm 13 and the lower section 6.

95 From the foregoing it will be seen that due to the angle at which the arms 23 are disposed, the stylus support is moved to the center of the reproducer after the same has been moved laterally, due to the contact of the stylus carried by the stylus member, with an irregularity on the record tablet.

100 Depending ears 25 form a part of the stylus support 19, through which ears extends 105 the pin 26 that connects the stylus arm 27 to the stylus support, one end of the stylus arm being provided with an opening to accommodate one end of the rod 28, the opposite end of the rod being positioned in 110

the securing means 29 that has connection with the diaphragm 9 at a point centrally thereof.

5 Positioned within the socket member formed in the free end of the stylus supporting arm 27 is the usual stylus 30 which moves in the sound grooves of the record tablet, to transmit certain movement to the diaphragm 9.

10 In the use of the reproducer constructed in accordance with the present invention, it will be seen that the body portion of the reproducer moves in a true plane at all times, all irregularities or vibrations which 15 are ordinarily directed to the body portion of the reproducer, being compensated for by the movement of the stylus support 19, and the stylus supporting arm 27.

What is claimed as new is:—

20 In a reproducer, a body portion including separable sections, a diaphragm positioned between the sections, an arm secured to the body portion and having a right angled end arranged in spaced relation therewith to 25 provide a bearing, a vertical pin arranged

between the body portion and bearing, a bearing member mounted intermediate the ends of the pin, a stylus support pivotally connected to the last mentioned bearing member and adapted to move in a vertical 30 plane, a spring member having connection with the stylus support to normally hold the stylus support downwardly, said stylus support having a central opening, a rod having connection with the diaphragm and extending through the central opening, a stylus arm pivotally mounted on the stylus support, said rod having connection with the stylus arm, and a support for the outer end of the stylus support to permit the stylus support to move vertically and laterally.

35 In testimony that we claim the foregoing as our own, we have hereto affixed our signatures in the presence of two witnesses.

CHARLEY REUTER.
OSCAR SCHILLING.
